UNITED STATES PATENT OFFICE

JOHN S. NORTON, OF SAN FRANCISCO, CALIFORNIA, ASSIGNOR OF ONE-HALF TO WIL-
LIAM F. HOLLINGSWORTH, OF SAN FRANCISCO, CALIFORNIA

WELDER'S HOOD

Application filed March 31, 1931. Serial No. 526,723.

My invention relates to improvements in welder's hoods and it consists of the combinations, constructions and arrangements hereinafter described and claimed.

5 An object of my invention is to provide a welder's hood which has novel chin actuated means for moving the dark glass into inoperative position when the operator desires to view the work through the clear protecting glass. The protecting glass is transparent and is removably secured to the hood, but remains in a fixed position when the dark glass is moved.

10 A further object of my invention is to provide a device of the type described in which the dark glass is held in raised position by a novel catch mechanism and remains in this position until the chin actuated member is again depressed.

15 20 Other objects and advantages will appear in the following specification, and the novel features of the device will be particularly pointed out in the appended claims.

My invention is illustrated in the accompanying drawing forming a part of this application, in which

Figure 1 is a vertical section through the device;

Figure 2 is a front elevation of the device;

30 Figure 3 is a rear elevation;

Figure 4 is a section along the line 4—4 of Figure 2; and

Figure 5 is an enlarged view of the catch mechanism.

35 In carrying out my invention I make use of a welder's hood 1 having the usual head band 2 and an opening 3 in its front face 4.

40 A plate 5 is secured to the front face 4 and covers the opening 3. A cross section through the plate 5 is shown in Figure 4 and it will be seen from this figure that rivets 6 or other suitable fastening means secure the plate to the hood.

45 The plate 5 is provided with an opening 7 and carries an inwardly extending flange 8 that borders the opening. An outwardly extending flange 9 extends around the opening 7 and has one side provided with a slot 10 (see Figure 4) for removably receiving a transparent protecting glass 11. Figure 2

shows leaf springs 12 and 13 struck up from the inwardly extending portions 14 of the flange 9, the springs engaging with the glass 11 for holding it in position. The spring 13 bears against the outer face of the glass 55 while the spring 12 bears against the edge of the glass.

The plate 5 is provided with guides 15 and these slidably receive a frame 16 of the shape shown in Figure 4. The frame 16 carries a 60 dark glass 17 and this is held in place by leaf springs 18. When the frame 16 is in normal position the dark glass 17 covers the opening 7 and protects the eyes of the welder.

65 The means for raising and lowering the dark glass 17 is shown in Figures 1 and 3. A link 19 is connected to the top of the frame 16 and in turn is connected to one end of a lever 20. The lever is pivoted at 21 and has its other end connected to a slide 70 22 at 23. A slot 24 is provided in the slide 22 and receives a guide pin 25 that in turn is carried by the plate 5. A rack bar 26 is connected to the slide 22 and adjustably carries a chin actuated member 27.

75 A depressing of the member 27 by the chin of the operator will through the mechanism just disclosed raise the frame 16 and move the dark glass 17 out of registration with the window 7. The clear glass 11 remains in the same position during the movement of the dark glass. The operator can now see the work without the necessity of raising the clear glass. The mechanism for raising the colored glass is of less weight 80 than that required in raising the dark glass and the clear one.

85 I provide a novel catch mechanism for holding the dark glass in raised position until the chin actuated member 27 is again depressed. In Figures 3 and 5 I show a bar 28, U-shaped in cross section, pivotally secured to the frame 16 at 29. A catch 30 is carried by the plate 5 and bears against the edges 31 of the bar 28. An L-shaped guide 32 90 also carried by the plate 5 has a portion extending over the bar 28. During the upward movement of the frame 16 the bar 28 is raised and the catch 30 moves along the edges 31 95 until it registers with notches 33 in the two 100

sides of the bar 28. A spring 34 secured to the bar 28 in the manner shown in Figure 5 moves against the L-shaped guide 32 and causes the catch 30 to be received in the notches 33 when the frame 16 is in its uppermost position. The frame is held in this position until the operator again depresses the chin actuated member 27.

When the operator does depress the member 27, the bar 28 is raised still further and this causes the catch 30 to move out of the notches 33 and to engage with the lower end of a trigger 35. This trigger is pivoted to the bar at 36 and its upper end is normally in a position to uncover the notches 33. The catch will swing the trigger 35 into a position where the upper portion 37 of the trigger will cover the notches 33.

A releasing of the chin actuated member 27 will now permit the frame 16 to drop by gravity and this will cause the catch 30 to strike the upper portion 37 of the trigger and this portion will act as a bridging member for causing the catch to move past the notches 33 and permit the frame 16 to move back into normal position. The downward movement of the bar 28 is so rapid that the catch 30 will strike the bridging portion 37 and will be deflected out of the notches 33 even though the trigger 35 is only pivotally supported. During this movement the trigger 35 is swung into the position shown in Figure 3 and the notches 33 will be uncovered and ready for the next operation of the device.

Although I have shown and described one embodiment of my invention it is to be understood that the same is susceptible of various changes and I reserve the right to employ such changes as may come within the scope of the claims hereto annexed.

I claim:

1. A welder's hood having an eye opening therein, a framed protecting glass movable vertically into and out of registration with the opening, and chin-actuated means connected to the top of the frame for lifting the glass out of registration.

2. A welder's hood having an eye opening therein, a framed protecting glass movable vertically into and out of registration with the opening, and chin-actuated means connected to the top of the frame for lifting the glass out of registration, said means comprising a link connected to the top of the frame, a lever pivoted to the hood and having one end connected to the link, a slide connected to the lever and extending along the side of the opening, and a chin rest secured to the slide.

JOHN S. NORTON.
